UNITED STATES PATENT OFFICE.

JAMES S. ATTERBURY AND THOMAS B. ATTERBURY, OF PITTSBURG, PA.

IMPROVEMENT IN KEROSENE-LAMPS.

Specification forming part of Letters Patent No. 37,267, dated January 6, 1863.

To all whom it may concern:

Be it known that we, JAMES S. ATTERBURY and THOMAS B. ATTERBURY, of Pittsburg, county of Allegheny, and State of Pennsylvania, have invented a new and improved lamp for burning coal and other volatile oil; and we do hereby declare that the following is a full and exact description thereof, reference being had to the accompanying drawings, and letters of reference marked thereon, like letters in the several figures indicating the same parts, and in which drawings—

Figure 1 is a vertical sectional view of our improved lamp. Fig. 2 is a perspective view of the lamp collar shown in position in Fig. 1. Fig. 3 is an inverted perspective view of the lamp-collar shown in Fig. 2, and Fig. 4 a partial enlarged sectional view of the lamp shown in Fig. 1.

The object of our invention is the construction of a lamp, by means of which the volatile oils now in common use—such as coal and paraffine oils—may be utilized for illuminating purposes without endangering the explosion of the lamp in which such oils may be burned. For such purpose we construct the body A of our lamp of glass, and so connect the burner D therewith that the heat of the lamp-flame communicated to the burner B shall not be transmitted to the body A of the lamp and the oil contained therein. To effect this we construct a detached glass-collar, C, as shown in Figs. 2 and 3, having concentric flanges or rims c' and c², as shown, said flanges or rims being so formed in respect to the neck d of the lamp that when placed in position, as shown in Fig. 1, the flange c' will rest upon the top of the neck d, and the flange or rim c² will rest upon the shoulder d' of the lamp, and this collar may be made of earthen-ware, porcelain, glass, or other like vitreous or argillaceous material. The collar C, which, in the process of manufacture, may be either pressed or blown, is provided with a brass screw hoop, e, such hoop being set within the collar by pressing the hot glass on and around the hoop while forming the collar, and the hoop being held in position therein, as represented in the figures, by the contraction of the glass in the act of cooling, thus dispensing with all cements usually employed to effect

the union of the parts, one of which is of glass and the other of metal. The hoop e, as clearly shown in Fig. 4, is provided with a female screw to receive the male screw formed upon the base of the metal burner B, and thus effect the union of the collar and the burner, as indicated in Fig. 1.

The hoop e, it will be observed by reference to Fig. 4, does not extend to the bottom of the rim c', so that when the collar is placed in position upon the lamp, as indicated in that figure, no portion of the hook will come in contact with the body of the lamp.

The glass collar C, when completed, as shown in Figs. 2 and 3, may thereafter be attached to the neck d of the lamp by means of proper cement f, interposed between the flange or rim c² and said neck, and such cement being forced into the annular space g', formed by the rims c' c², also subserving to prevent the transmission of heat to the oil contained in the lamp. These collars may be made as a separate manufacture, as shown in Figs. 1 and 2. We have thus shown a lamp for burning volatile oils in which the metal used and liable to become heated is effectually insulated from the oil-containing reservoir, and thus obviating all danger of overheating the oil and so causing the explosion of the lamp.

We have shown in the construction of the glass collar C a particular mode of connecting the metal screw hoop e thereto, and it is obvious that said hoop might in like manner be applied directly to the neck d of the ordinary lamp-body A, (shown in Fig. 1;) but this we do not claim in the present application for a patent.

What we claim in this application for a patent for improvement in lamps for burning coal, paraffine, and other volatile oils, and desire to secure by Letters Patent of the United States, is—

As a new article of manufacture, a glass collar, C, constructed and applied to a lamp in the manner and for the purpose substantially as set forth.

J. S. ATTERBURY.
T. B. ATTERBURY.
